John W. Maupin
ATTORNEY

UNITED STATES PATENT OFFICE.

GEORGE A. LONG, OF SEATTLE, WASHINGTON.

TRACK LUBRICATOR.

Application filed June 11, 1923. Serial No. 644,791.

To all whom it may concern:

Be it known that I, GEORGE A. LONG, a citizen of the United States, residing at Seattle, in the county of King and State of Washington; have invented a new and useful Track Lubricator, of which the following is a specification.

My invention relates to improvements in track lubricators adapted for installation on 10 all vehicles that run on tracks, and the principal objects of the invention are to provide a track lubricator which is simple and economic in design, durable and substantial in construction, efficient and reliable in operation, and which will prolong the life of the rails by automatically supplying oil to the track at all points where lubrication is desired. Other objects are to provide automatic means whereby the device will pass 20 all track obstructions without damage and will immediately adjust itself to again supply lubricant to the needed points. Further objects are to provide a track lubricator that is self lubricating and which embodies 25 means for preventing the application of oil to points where lubrication would be detrimental.

With the above and other objects in view which will appear as the description proceeds, the invention consists of the novel construction, adaptation, arrangement and combination of parts hereinafter described and claimed. These objects are accomplished by devices illustrated in the accompanying drawings, wherein—

Figure 1 is a view in side elevation showing the device installed on a fragmentary part of a vehicle;

Fig. 2 is a view in front elevation of the 40 same;

Fig. 3 is a top plan view of the ball and socket joint.

Fig. 4 is a view in central vertical section taken substantially on a broken line 4, 4 of 45 Fig. 3;

Fig. 5 is a view in central vertical section taken on a broken line 5, 5 of Fig. 3 and showing the ball partly in elevation;

Fig. 6 is a detail view in side elevation of 50 the nozzle; and

Fig. 7 is a view in front elevation of the same.

Referring to the drawings throughout which like reference numerals designate like 85 parts, the numeral 5 indicates a pipe which leads from an oil supply tank, not shown.

Said pipe connects with a ball and socket joint designated as a whole by the numeral 6.

The pipe 5 connects directly with a male 60 socket member 7 and the passageway through said pipe continues centrally through said male member as at 8. A bracket 9, integrally or fixedly secured to said male member, is bolted or otherwise secured 65 to a stationary part of the vehicle usually adjacent the foremost or lead wheel, such as the journal bearing 10, clearly shown in Figs. 1 and 2 of the drawings, and more fully hereinafter described.

A ball 11 fits snugly against the inner bearing surface of the male member 7 and a female socket member 12, secured to said male member, is adapted to retain said ball in its operative position. The lower flange 70 of said male member abuts against an annular shoulder 13 within said female member whose inner bearing surface is machined so that the ball will turn smoothly therein as may be readily understood.

Diametrically opposite spring pockets 14 are provided within the ball and socket joint 6 extending partly into the male member 7, ball 11, and female member 12 respectively, as shown in Figs. 3 and 4. Equalizer springs 15 are housed within said pockets with their upper ends bearing against said male member and their lower ends seated partly against said ball and partly against said female member for reasons presently set forth.

Another spring pocket 16, at right angles to the alignment of the pockets 14, extends partly within the male member 7 and partly within the ball 11 wherein a back spring 17 95 is seated. A pivot pin 18 is integral with or secured to said ball at a point diametrically opposite said back spring. Said pin works within a slot 19 provided within said male and female members which limits the vertical and restricts the horizontal rotary movement of said ball.

A vertical conduit 20 passes through the ball 11 and is arranged to register with the passage 8. Said conduit continues through 105 a depending pipe 21 secured to or integral with said ball. The lower portion of the female member 12 is provided with an enlarged opening 22 around said pipe to allow swinging movement of same when said ball 110 is caused to move on its axis.

A nozzle 23 is threadedly secured to the

lower end of the pipe 20. The discharge end 24 of said nozzle is enlarged and a sponge or other similar substance is usually placed therein to restrict the flow of oil. A screen plate 25 is ordinarily secured over the outlet end to hold said sponge in place and grooves 26 are provided in the sides thereof to allow the oil to spread. It will be understood that I do not limit myself to this specific design of nozzle for the reason that street railway systems use a flange head rail and said nozzle may have a double outlet for the purpose of oiling the rail flange as well as the ball.

15 As hereinbefore stated the device is attached to a part of the vehicle which retains a fixed relation with the track and in such position that the discharge end 24 of the nozzle will normally follow the curve and 20 camber of said track. Ordinarily two lubricator devices are used on each vehicle or train, one being secured on each side adjacent the inner side of the foremost wheel and at a sufficient distance forward, or aft, 25 therefrom to prevent contact therewith when the device meets with an obstruction as indicated in Fig. 1 of the drawings.

When the nozzle 23 meets with an obstruction the equalizer springs 15 will absorb the 30 shock and allow said nozzle to swing over the obstruction, with the ball 11 acting as the pivotal center, and said springs will immediately bring the nozzle back to its normal position in engagement with the inner 35 side of the rail head.

The back spring 17 will normally hold the nozzle 23 against the ball of the rail and the 40 pivot pin 18, on coming in contact with the upper wall of the slot 19, will prevent said nozzle from riding on top of the rail tread, and in fact will restrict its movement to prevent oil from being spread on top of the 45 rail head where lubrication is to be avoided.

The discharge end 24 of the nozzle is 45 rounded so that same may ride over an obstruction and slide easily back to its normal position. It will thus be seen that the device is adapted to pass all track obstructions such as frogs, cross-overs, and all other obstacles 50 met with at switches, crossings, turn-outs and other intersections.

The oil may either be supplied by gravity or by forced feed using steam or compressed air. It will be obvious that the ball and 55 socket joint 6 will be self-lubricating, and the copious supply of oil always present at the discharge end of the nozzle 23 will serve to prevent wear of same. Said nozzle and the screen plate 26 are independently detachable and may be readily replaced. The device as a whole is also adapted to function when the vehicle is backing, and it is self 60 evident that same may be mounted to the rear of the wheel if so desired.

On straight stretches of track the lateral 65 clearance of the rails will serve to lessen the discharge of oil, while on curves the reduced speed of the vehicle together with the centrifugal force pushing the flanges of the 70 wheels against the outer rail will cause a plentiful supply of oil to be furnished where lubrication is primarily desirable.

It is well understood that the rolling action of the wheels on poorly lubricated 75 track, particularly at places where the wheel flanges are in direct contact with the rail heads, results in metallurgical decomposition, abrading and detrusion of the inner rail balls which become beaded, ravelled and broomed. In addition to the damage to the 80 rails this rail-wear causes an increased resistance to traction, waste of energy, wearing of the wheel flanges, and danger of derailment. The primary object of the invention is, in so far as possible, to decrease 85 the percentage of this enormous loss.

From the foregoing description taken in connection with the accompanying drawings, the form of construction and method of operation of my track lubricator will be 90 readily apparent to those skilled in the art to which the invention relates, and, while I have described the principle of operation in connection with the device which I now consider to be the best embodiment thereof, 95 it will be understood that the device shown is merely illustrative and that such changes may be resorted to as are within the scope and spirit of the invention.

Having thus described my invention what 100 I claim and desire to secure by Letters Patent is:—

1. A railway track lubricator comprising an oil supply pipe, means carried by a vehicle for supporting said lubricator, a nozzle, a ball and socket connection between 105 said pipe and nozzle, springs housed within said lubricator for regulating said connection to yieldingly hold said nozzle in its normal depending position, and another spring housed within said lubricator adapted 110 to retain the discharge end of said nozzle in engageable relation with the track of said vehicle.

2. A railway track lubricator comprising 115 an oil supply pipe, means carried by a vehicle for supporting said lubricator, a nozzle, a screen plate on said nozzle, a ball and socket joint between said pipe and nozzle, a pivot pin within said joint arranged to limit the vertical and restrict the horizontal 120 rotary movement of same, springs housed within said lubricator and interposed between the male and female members of said joint to yieldingly retain the nozzle in engageable relation with the track of said vehicle substantially as specified.

GEORGE A. LONG.
